UNITED STATES PATENT OFFICE.

WARREN G. CHILD, OF OGDEN, UTAH.

FRAMING SQUARE.

Application filed February 2, 1926. Serial No. 85,489.

The invention is embodied in that type of framing squares especially adapted for use by carpenters and others in marking angles for framing and for other purposes in building constructions. The instrument of my invention is of the straight edge type having adjustable blades which permit both a sliding and a rotary movement, in combination with other elements of parts which adapt the instrument for facile use in various ways.

By the utilization of my invention I provide an instrument having parts that are capable of compact arrangement when not in use, and which are readily accessible for selective use when required.

The invention consists in certain novel combinations and arrangements of parts as will hereinafter be more fully pointed out and claimed.

In the accompanying drawings I have illustrated one complete example of the physical embodiment of my invention wherein the parts are combined and arranged in accord with the best mode I have thus far devised for the practical application of the principles of my invention.

Figure 1 is a perspective view of the instrument with its parts in folded or compact form.

Figure 2 is a plan view of the instrument on a reduced scale with the parts extended for purposes of illustration.

Figures 3 and 4 are detail sectional views, enlarged, of the pivot and clamping parts.

In the preferred form of my invention as illustrated in the drawings the parts may be of wood, metal, or combinations of wood and metal, or of other suitable material, and the stock or body of the instrument comprises a flat blade 1 having ruling or straight edges at its parallel sides and a body portion 2 from which the integral blade is offset.

The stock is fashioned with a slot 3 or recess cut out between the body portion 2 and the blade 1. The body portion is foreshortened and terminates a considerable distance from the end of the blade, while the recess terminates substantially the same distance from the other end of the body, thus providing a broad flat blade, a body portion approximately half the width of the blade, and a recess having one of its walls flush with the upper face of the blade 1.

The top of the foreshortened body portion is cut away as at 4 and the cut away portion

terminates in a shoulder 5 located near one end of the instrument with one portion extending at right angles to the longer axis of the instrument and terminating in an arcuate portion or rounded edge.

In the cutaway portion or recessed top of the body 2 a square blade 6 is adapted to seat, said blade being approximately the same width as the body portion and provided with a rounded end which is perforated to fit over a screw 7 having a head and passed upwardly through an opening in the body of the stock. A clamp nut 8 is provided for the threaded projecting end of the screw by means of which the square blade may be secured in angular adjusted position as in Figure 2, or clamped in its normal position as in Figure 1. At one corner of its free end the square blade is fashioned with a notch 9 which co-acts with a pin 10 in the body of the stock as a guide and for retaining the square blade in normal position.

From the end of the stock or body in which the square blade is pivoted, the body projects in the form of a tongue, and between this tongue and the main blade 1 the recess or slot 3 is provided for a complementary pair of adjustable angle blades 11 and 12, both of which are fashioned with longitudinally extending slots 13 and pivoted on a screw 14 for sliding and rotary movement with relation to the stock. When not in use these blades, which are substantially the width of the body portion 2, are stored in the recess or slot 3 as indicated in Figure 1. In Figure 2 the adjustability of these blades is illustrated and a clamp screw or thumb screw 14 is provided with a thumb nut 15 for securing the slotted blades in stored position. The blades are independently adjustable on the screw with a rotary motion to desired angular position or slidable with relation to the screw, and when stowed away their pivoted ends terminate preferably at the end of the main blade 1. The inner ends of these angle blades are preferably beveled as at 16 and the end wall of the slot 3 is also beveled complementary thereto as indicated in Figure 2 by dotted lines.

At the side of the body of the stock and foldable on the top face of the main blade 1 I use a 45° arm 17, shorter than the square blade and the angle blades, and pivoted on the main blade by means of screw 18 threaded in the arm. When not in use the arm

lies against the adjoining face of the body of the stock as in Figure 1 and is retained there by the frictional engagement of the heads of the screw 18 with the blade 1 and 5 arm 17 respectively.

As best seen in Figure 1 the end of the main blades to which the arm is pivoted is cut off at an angle of 45° as indicated at 19 and the pivot end of the arm is cut off in the 10 opposite direction also at an angle of 45° thus providing for an arrangement of the arm at an angle of 45° as indicated in Figure 2.

The top face of the square blade 6 and 15 the top of the cut away body portion of the stock are both graduated in inches with a measuring scale and the top face of the scaled body is provided with angle lines at D for use with the blade 6 in addition to its 20 right angle or 90° marking. In Figures 1 and 2 it will be seen that the main blade is also marked with angle lines at A, B and C for use with the two slotted adjustable blades 25 11 and 12 either jointly or selectively.

25 The various uses of the framing square will be obvious to one skilled in the use of the instrument. For instance, to mark rafters for a bottom cut, the stock is placed against the top edge of the rafter and the 30 square blade 6 is turned to coincide with the selected or required line adjacent to the pivot or screw 7, and the edge of the blade 6 is used for marking the cut, as applied to common or jack and valley rafters.

35 To mark a cut for the top or ridge end of the rafter, the stock is placed against the top edge of the timber, then the square blade 6 is swung on its pivot to coincide with the selected line and the nut 8 clamped to secure the blade. The rafter may then be 40 marked for the top cut of common or jack rafters and valley rafters.

For marking the top end of jack rafters, 45 both the slotted angularly adjustable blades 11 and 12 are used by first swinging them around on their pivots to bring the beveled ends 16 below the stock in Figure 2.

Blade 12 is then turned so that its outer edge will coincide with the selected line of 50 group A and blade 11 is turned to having its outer edge coincide with the selected line of group C. Blade 12 is now used to mark the side cut of a jack rafter and blade 11 is used to mark the plumb cut of the jack.

For marking hips and valleys the arm 17 is 55 swung to its relative position in Figure 2 but placed perpendicular with the intersection of the rafter and hip and the angularly disposed stock is then used for the markings.

Having thus fully described my invention, 60 what I claim as new and desire to secure by Letters Patent is—

1. The combination with a stock comprising a broad flat main blade and a narrower body portion united to said blade so that a recess is formed between them, of a pair of rotatable and slidable slotted angularly adjustable blades a pivot screw passed through said main blade and body and said slotted blades, and a thumb nut for clamping 70 said parts.

2. The combination with main blade having a beveled end and a body portion united to said blade so that a recess is formed between them, of an arm pivoted on the blade and having its outer edge adapted for alignment with said beveled end, the pivoted end of said arm being cut at a reverse bevel to the beveled end of the main blade for co-action with a side face of the body portion. 80

3. The combination with a stock comprising a broad flat main blade and a body portion superposed thereon and terminating short of the end of said blade and united to said blade so that a recess is formed between them having its lower wall flush with the top face of the main blade, of a pair of angularly adjustable slotted blades adapted to fit into said recess and provided with complementary beveled ends, a pivot screw passed through said main blade, body and adjustable slotted blades, and a clamp nut on said screw. 85 90
